COLLAPSIBLE GO-CART.

1,124,151.

Specification of Letters Patent.

Patented Jan. 5, 1915.

Application filed February 12, 1910. Serial No. 543,610.

To all whom it may concern:

Be it known that I, MARSHALL B. LLOYD, a citizen of the United States, and a resident of Menominee, county of Menominee, 5 and State of Michigan, have invented certain new and useful Improvements in Collapsible Go-Carts, of which the following is a specification.

My invention relates to the collapsible or 10 foldable type of go-carts or baby-carriages. The principal feature of my invention lies in the provision of a carriage structure which by a single movement may either be completely and quickly folded into a compact 15 parcel or opened up and transformed into condition for use. This I have made possible by providing a structure having a main frame upon which I have mounted all of the movable parts which are adapted to 20 be folded or collapsed. These movable parts are all adapted to operate relatively to the main-frame and when collapsed are adapted to assume positions in intimate compact relation to said frame, the said parts 25 being so connected with each other that the movement of a certain part, preferably the propelling or operating handle, will cause all of the parts to assume simultaneously one or the other of these positions, either 30 open or folded.

In the preferred form of my invention the main frame is a horizontal rectangular shaped structure above which and pivotally connected to which is arranged the body-frame or superstructure which carries the usual handle, canopy, seat and front apron. Below the main frame and pivoted thereon, at its lower side edges, to swing or fold inwardly into parallel relation with said 40 main-frame are supplemental wheel-frames. The body-frame and supplemental wheel-frames are interconnected by means of a system of levers and braces or links so arranged that when the body-frame is collapsed it will simultaneously cause the supplemental wheel-frames to be folded inwardly and when opened will cause the wheel-frames to be projected outwardly. Preferably an operating handle pivotally 45 related to the main-frame is provided for controlling the actuation of said structure, the arrangement being such that by a single movement of the handle in one direction, preferably forward, the entire carriage will 50 be caused to fold at once into a compact and

conveniently portable parcel, and likewise by a corresponding single reverse movement it will be opened.

Another feature of my invention lies in arranging certain of the parts, which operate to fold the supplemental wheel-frames, in such a manner that when the carriage is 60 in use they will serve as braces to rigidly maintain the parts of the carriage in their extended positions.

Another feature lies in the association with the handle and body frame, in a conveniently accessible position, of locking members which are adapted to secure the structure against collapse when it is in use. 70

For a more complete understanding of my invention reference may be had to the accompanying drawings forming a part of this specification, and in which:

Figure 1 is a side elevation of a baby- 75 carriage or go-cart illustrating one embodiment of my invention; Fig. 2 is a view of the underside of said structure opened and showing the main-frame together with the cross-bars and braces for folding inwardly 80 the supplemental wheel-frames; and Fig. 3 is a lower plan of the cart in folded condition.

Like parts will be referred to by similar reference characters throughout the several 85 views.

In the structural embodiment of my invention shown in the drawings, I have provided a main-frame 1, a body-frame or superstructure 2, arranged to fold thereupon, and a pair of supplemental running-gear frames 3 arranged below the main-frame, said running-gear frames being preferably pivoted one on each side of said main-frame in such a manner that they can 90 be collapsed and folded inwardly into intimate relation with and beneath the main-frame in order to form a compact parcel when the go-cart is not in use. I construct the main-frame 1 as a substantially plain 100 open rectangular horizontal frame comprising a pair of side bars 1' and a pair of end bars 1'' rigidly joined together, either integrally or otherwise, at the corners to constitute a foundation on which I build the 105 superstructure 2 and on which the wheel frames 3 are pivotally mounted.

Each of the supplemental running-gear or wheel-carrying frames 3 comprises a horizontal bar 3' having downwardly 110

turned ends to which are rigidly secured forward and rear vertical uprights 6 for transverse swinging connection to frame 1. The said side frame parts 3' and 6 for each 5 side are preferably formed integrally from a single strip of metal looped downwardly at the ends of the horizontal part 3' with the ends of the strip extended upwardly to form the uprights 6. Each of the downwardly projecting loop-portions is formed 10 to rigidly clasp and securely hold the inner end of a short journal stud 5 on the outwardly projecting portion of which is journaled one of the road wheels 4. The upper 15 ends of the upright 6 are pivoted at points 7 to lugs 8 depending from the underside of the main frame 1. Each frame 3 carries a front and a rear wheel 4 on its respective side of the main frame, and is adapted to be 20 swung inwardly and upwardly on the pivots 7 into substantially parallel relation with the main-frame 1. The wheels being thus securely mounted on the opposite ends 25 of the side-frames 3, and parallel therewith, are carried thereby into compact relation to the main frame when the frames 3 are retracted or folded up against the underside of the main frame.

Attached to the main frame by pivots 10 30 on each side and on both the front and rear portions thereof are cross-bars or operating yokes 9. These cross-bars are U-shaped in form, their ends projecting upwardly, and are adapted to swing or oscillate backwardly and forwardly beneath the main frame on their pivots 10, as shown by dotted lines on Fig. 1. These cross bars 9 are connected for simultaneous movement by a longitudinal link 11 which pivotally 35 connects the middle or lowermost parts of the two bars. The cross bars 9 are also linked to the wheeled frames 3 by diagonal braces or links 12 which serve to swing the side frames in and out as the cross bars are 40 swung back and forth. These brace rods, as clearly shown in Figs. 2 and 3, are arranged 45 diagonally and serve to rigidly brace the wheeled-frames in open position. These brace-rods or links 12 are pivotally connected to said cross-bars 9 and frame-bars 50 55 55' by universal joints, desirably of the construction shown at 13 and 14, the braces being looped at their ends, and entering perforated lugs provided therefor on the wheel-frames 3 and engaging similar or equivalent pivoting means on the cross bars 9. These peculiar joints which are very cheaply produced readily permit the brace rods 12 to adapt themselves to the relative change in 60 position and direction of movement of the cross-bars 9 and the supplemental wheel-frames 3, when said wheel-frames are oscillated or swung either outwardly or inwardly in opening or closing the cart. 65 When the vehicle is in use the braces 12 are

spread widely apart to hold the wheel-frames projected in vertical position beneath the side bars of the main frame, but when the device is folded the inner ends of the braces engaging the controlling yokes 70 or cross-bars 9 are drawn diagonally upward toward the rear, and said braces are partially folded together to a more parallel relation, their forward ends being drawn inwardly and upwardly toward the center 75 of the main-frame and thus serving to swing the wheel-frames 3 inwardly in substantially parallel relation to the main frame.

Above the main-frame 1 is the superstructure 80 80 which is arranged in the form of a pair of duplicate parallelograms one on each side of the main-frame. Each parallelogram comprises a side bar 1' of the main-frame 1, an upwardly projecting bar 20 at 85 the forward end and a handle bar 21 projecting upwardly at the rear end, the said bars 20 and 21 being operatively connected together at or near their upper ends by links or arm-bars 23 substantially parallel with the main-frame 1. The arm-bars are attached by pivots 24 and 25 to the bars 20 and 21 respectively.

The rear bars 21 have preferably integral extensions 30 which are connected transversely at their upper ends and are adapted to serve as an operating handle for the carriage. The bars 21 with their extensions 30 and with the upper cross connection constitute as a whole a propelling handle, 90 which is also a lever which is pivoted at 22 to the main frame 1, and serves as a convenient operating means by which to collapse the entire structure.

The bars 20 are in reality merely upward 105 extensions of the forward yoke or cross-bar 9 and together serve as one arm of a lever of which the downwardly projecting U-shaped cross-bar is the other arm, the complete yoke or cross bar lever 9 being pivoted 110 at the forward pivot points 10. This cross bar lever, as shown, serves as the operating member or connection extending between the arm-bars 23 operated by the propelling handle and the braces 12 which control the 115 wheel frames 3, to cause the said wheel frames to be retracted or folded inwardly when the vehicle is collapsed, and to be projected or unfolded outwardly when it is 120 opened for use.

Extending between a point 27 on each handle bar 30 and a point 28 on each arm-bar 23 is a toggle 26 which is arranged to lock and hold rigid the superstructure when open and to thereby prevent collapse of the folding mechanism when the carriage is in use and when it is being pushed along by the handle. By pressing upward at the locking hinge or knuckle 29 of the toggle, as indicated by the arrow on Fig. 1, the tog- 125 130

gle will double up and will then permit the handle to be moved or rotated forward as indicated by the dotted lines in Fig. 1 to collapse the entire carriage.

5 As before noted, the forward cross bar 9 and its upward extensions 20 form a lever pivoted at 10 to the main-frame. This lever, as stated, serves as a means for transmitting movement between the superstructure and the supplemental wheel-frames. Manifestly, then, if the operating handle 30 be released, by raising the toggle lock 29, and be pushed or rotated forward, it will cause the links or arm bars 23 and the cross-bar extensions 20 to move forward to collapse the superstructure. The forward cross-bar 9 will at such time be swung in the opposite or rearward direction on its pivot 10, and through the link 11 will transmit a similar movement to the rear cross-bar 9. This rearward movement of the cross-bars 9, as before explained, withdraws the frames 3 from their extended positions and folds them inwardly against and beneath the main-frame. The handle 30 is swung on the pivot 22 sufficiently to bring it into substantially parallel relation to the main-frame 1. The arm-bars 23 and the cross-bars 9 are thereby necessarily moved 20 into position closely adjacent to the upper-side of and substantially parallel with the plane of the main-frame. The wheel-frames 3 and the wheels thereon are also folded to a similar position parallel with 25 and adjacent to the underside of the main-frame.

It will thus be seen that in this structure the swinging forward of the operating handle on its pivots, when it is desired to fold 40 the vehicle, will simultaneously cause the superstructure to collapse and the wheel-frames to fold or swing into intimate relation with the main-frame 1. Furthermore, the braces 12 are diagonally related to the 45 horizontal bars 3' and when the carriage is opened by the opening out of the handle the braces 12 push out mutually wedgingly by a kind of toggle action, and the wheel frames are thereby restored to their normal 50 upright positions, and the braces 12 serve to rigidly and strongly hold them in said normal positions, thereby preventing the wheel-frames from caving in or collapsing while the carriage is in use.

55 The usual body 35, which may be made of cloth or any suitable material, together with its seat back 36 and the apron 37 may be supported in the superstructure in any suitable manner. In the structure shown in 60 the drawings, the body is suspended from the horizontal arm-bars 23, the apron 37 being supported by suitable means at the forward end of the main-frame. The usual canopy 33 is shown pivoted at 34 to the 65 horizontal links or arm-bars 23. The body

35, front apron 37, and canopy 33 being of such a nature that they are readily modifiable and not being claimed in this application need not be particularly described herein.

All novel features disclosed in this application, but not specifically claimed therein, are reserved for my copending application 543,611 which was filed simultaneously therewith and which pertains to the more specific features of my improved go-cart. 70 75

As many modifications of my invention will readily suggest themselves to one skilled in the art, I do not confine or limit my invention to the specific structure herein shown and described. 80

Having thus described my invention, I claim as new and desire to secure by Letters Patent:

1. In a collapsible baby-carriage, the combination with a main frame, of a handle 85 and a pair of supplemental wheel-frames associated with said main-frame and adapted to swing into parallel relation to said main-frame, yoke members pivoted upon and depending from said main-frame, links 90 connecting said yoke members with said wheel frames, and means interconnecting said handle and said yoke members to swing said wheel-frames into parallel relation when pressure is applied to said handle. 95

2. In a collapsible baby-carriage, the combination with a main frame, of a handle pivoted to said frame, running gear frames suspended at the sides of said frame and adapted to swing inwardly into substantially parallel relation to said frame, a lever pivoted to said frame, a pair of yokes swingably mounted on said main frame, a link interconnecting said yokes below said main frame, brace links connecting said wheel 105 frames with said yokes, means connecting one of said yokes with said handle for swinging said gear frames into parallel relation with said main frame.

3. In a collapsible baby-carriage, the combination with a rectangular main frame, of a collapsible superstructure supported by said frame and adapted to collapse into intimate relation to said frame, supplemental wheel frames adapted to fold inwardly, 110 cross bars pivoted to and depending from said main frame, braces universally jointed to said supplemental frames and to said cross-bars, a link connecting said cross bars, and extensions on one of said cross-bars 115 forming a part of said superstructure.

4. In a collapsible baby-carriage the combination with a rectangular open main frame, of supplemental wheel-frames pivotally secured to the sides of said main-frame and adapted to fold inwardly beneath said frame, transverse bars pivoted to the sides of said main frame, one of said bars having extensions projecting upwardly, a collapsible superstructure formed in part 125 130

by said extensions, brace rods extending between said cross-bars and said wheel frames, and a link connecting said cross-bars.

5. In a collapsible baby-carriage the combination with a main-frame, wheel frames adapted to fold inwardly, a body frame adapted to collapse into intimate relation to said main frame, a depending extension on the forward part of said body frame, 10 links connecting said wheel frames with said extension for folding said wheel frames simultaneously with the collapse of said body-frame, and a handle for collapsing said body-frame.
- 15 6. A collapsible go-cart comprising a main frame, in combination with wheels, wheel frames pivotally joining the wheels to the main frame, members fore and aft of said main frame and movable with respect 20 to the main frame, diagonal braces extending from said members to respective wheel-frames, and mechanism for moving said members with respect to the main frame to fold and open the wheel frames.
- 25 7. A collapsible go-cart comprising a main frame, in combination with wheels, wheel-frames pivotally joining the wheels to the main frame, members positioned fore and aft on said main frame and movable 30 with respect to the main frame, diagonal braces extending from said members to respective wheel-frames, mechanism for moving said members with respect to the main frame, and a locking device for securing said members and main frame in fixed relation to secure the wheels in opened position.
- 35 8. In a collapsible go-cart a substantially horizontal main frame, in combination with wheel-frames pivotally attached to the sides

of the main frame, a wheel-frame operating member movably attached to said main frame, and depending below said frame, and diagonal actuating brace rods extending therefrom to said wheel-frames for communicating the movements of said member to said wheel-frames, substantially as described.

9. A multiple part toggle lever operating mechanism for collapsible go-carts comprising main arms, a middle link, U-shaped in cross-section and containing the ends of said arms, and two pivots joining the link to respective ends of the main arms, said pivots, arm ends and link being positioned to pass centers and assume a rigid position.

10. A collapsible go-cart comprising a main frame, in combination with supplemental wheel-frames pivoted on the sides thereof, wheel-frame actuating members pivotally arranged on said main frame, diagonal braces joining respective members with opposite points on said wheel frames, a propelling handle pivoted on the main frame, means connecting the handle with one of said members, through the medium of which relative movement of the main frame and handle is communicated to the wheel-frames, and a lock for securing the several parts in opened condition.

In testimony whereof, I have hereunto set my hand, this 29th day of January, 1910, in the presence of two subscribing witnesses.

MARSHALL B. LLOYD.
